UNITED STATES PATENT OFFICE.

FRANK J. SPRAGUE, OF NEW YORK, N. Y.

ELECTRIC RAILWAY.

SPECIFICATION forming part of Letters Patent No. 340,685, dated April 27, 1886.

Application filed November 24, 1885. Serial No. 183,894. (No model.)

To all whom it may concern:

Be it known that I, FRANK J. SPRAGUE, of New York city, in the county and State of New York, have invented a certain new and 5 useful Improvement in Electric Railways, of which the following is a specification.

In an application for patent filed by me of even date herewith I have set forth means for braking an electric railway car or train, 10 such means being an improvement on those set forth in my Patent No. 318,668, dated May 26, 1885. In that patent the train was braked by increasing the counter electro-motive force of the motor until it should overcome the initial, whereby the dynamo-electric machine, which normally acts as a motor to propel the train, becomes a braking-generator, and the energy of the moving train is expended in current upon the line. In this case, after the 15 machine becomes a generator, it is necessary to continue to increase the field-magnet strength, because the decrease in speed of the train tends to diminish the counter electro-motive force, and this tendency has to be counteracted. When the limit of increase of field 20 strength is reached before the train stops, other means have to be employed, as stated in the patent referred to, to bring the train to a complete standstill. In the application mentioned this was accomplished by closing a local armature-circuit through a resistance, leaving the field-magnet in connection with the line, whereby the energy of the moving train was expended in said local circuit. 25 My present invention relates to an improvement upon this; and it consists, mainly, in placing in said local circuit the operating magnet or magnets of an electro-magnetic brake acting, when energized, upon the wheels 30 of the car. The power of this brake may be regulated by varying the strength of the field-magnet of the machine, or an adjustable resistance may be placed directly in the brake-circuit for this purpose, or both may be used. 35 I prefer to provide, also, means whereby, in case of any accident to the machine, or for any other purpose, the line-current may be thrown upon the brake-magnets to stop the train. 40 My invention is illustrated in the annexed drawings, in which Figure 1 is a plan view of a railway-car truck and motor with the con-

nnections in diagram, the same running under ordinary conditions; Fig. 2, a similar view of the same truck with the machine running as 55 a generator and the brake in action, and Fig. 3 a side view of an electro-magnetic brake which I prefer to use.

A is the truck of a car. B is the armature, and C the field-magnet, of the dynamo-electric 60 machine, mounted upon the truck and normally propelling or assisting to propel the car. It is preferred to place a motor upon each truck of each car of a train. Motion is communicated from the armature-shaft of the motor to the driving-axle D by cog-wheels E E.

F F are the main rails of the track. These form one side of the circuit, while the other is formed by the insulated intermediate rail, G.

H H are supply-conductors connecting the 70 track with the generating-station. (Not shown.) One terminal of the motor is a spring or brush, I, supported in any suitable manner and bearing on axle D'. The other is the contact-rollers J J, which run on intermediate rail, G. 75

The switches and regulating apparatus are, for clearness, shown in the drawings apart from the motor and car. It will of course be understood, however, that these devices are 80 placed in any convenient situation upon or within the car.

K is the field and armature regulating apparatus, such as is set forth in my Patent No. 321,150, dated June 30, 1885. It consists of 85 resistance-coils a a for the field-circuit, connected with short contact-blocks b b and long contact c, and coils d d for the armature-circuit, connected with short contacts e e and long contact f. Arms g g' travel on these blocks. 90

L is the brake-circuit switch. It has three stationary contact-plates, h h' h'', and a moving plate, i. It is adapted to close the armature to line, to close the armature upon the brake-circuit, or to close the line upon the 95 brake-circuit, as will be presently explained.

M is a simple circuit-reversing switch for the armature-circuit, used to change the direction of rotation of the motor.

N is an adjustable resistance for the brake-circuit.

When the regulating devices are as shown in Fig. 1, the machine is running as a motor, its circuits being as follows: from contact-

spring I by wire 1 to arms g g' of switch k , where the circuit divides, the field-circuit being by g' , coils a a , block e , wire 2 to field-magnet, and wires 3 3 to rollers J J , while 5 the armature-circuit is from g to block f , wire 4 to circuit-reverser M , wire 5 to commutator-brush, through armature-wire 6 to circuit-reverser again, wire 7 to plate h^2 of switch L , plate i to h' , wire 8 to wires 3 3, and to J J .
 10 When it is desired to stop the train, the arm g' is moved so as to cut out coils a a , strengthen the field-magnet, and increase the counter electro-motive force. This is continued until the counter electro-motive force overcomes the initial 15 and the machine becomes a generator, and afterward, as the train slows down, until all the coils a a are cut out of circuit. The current generated will then begin to drop, and the machine would again become a motor, and the 20 train would not be stopped; but when the two opposing electro-motive forces become equal, as will be shown by indicator S , of quantity and direction of current to still further brake the train, the switch L is shifted 25 to the position shown in Fig. 2, which disconnects the armature from the line and throws it on the brake-circuit, the field-magnet still remaining in connection with the line. The circuits are now as follows: The 30 field-circuit is the same as already described. The armature-circuit is from positive brush by wire 5, switch M , wires 13 and 9 to 10, where part goes to brake-magnets O O and part to magnets P P , thence by wire 11 to resistance 35 N , wire 12 to block h of switch L , contact i to h' , wire 7 to switch M , wire 6 back to other commutator-brush.

The brake which I prefer to employ—though any efficient form of electro-magnetic brake 40 may be used instead—consists of two electro-magnets, O O or P P , each of which has an iron core, k , having pivoted to it an arm, l , carrying an iron brake-shoe, m . Normally the brake-shoes are held away from the wheels 45 by a spring, n . The brake-shoes may have removable surfaces of non-magnetic material, if desired.

When the magnets are energized in the manner just explained, the brake-shoes become 50 magnetized therefrom, and are attracted by the iron wheels Q Q and drawn toward the same, so as to brake said wheels. A brake apparatus of this kind is preferably placed between the two wheels on each side of each car-truck. This brake acts the same, no matter in 55 which direction the current is. Its power may be regulated by adjusting resistance N or by regulating the strength of the field-magnet of the motor by the adjustment of arms g' , 60 which is the preferred mode of regulation; or both may be used.

I am aware that in electro-magnetic brakes it has been proposed to employ magnets with 65 movable cores attracted toward the wheels, and also magnets which themselves are movable bodily toward the wheels. I employ, as just described, pivoted movable extensions,

which is a simple construction, and permits of the ready removal of the wearing parts for repair or renewal.

In case of any accident occurring to the motor when it is desirable to quickly arrest the momentum of the train, the line-current may be thrown upon the brake-magnets by turning switch L to its third position, so that plate i bridges h h' . This makes the circuit from brush I , wire 1, regulator K , wires 4, 9, and 75 10 to brake-magnets, wire 11, resistance N , plates h i h' , wire 8, wires 3 3 to J J .

I do not claim herein, broadly, the local armature-circuit, or said local circuit including an adjustable resistance, when the field-magnet is normally connected with the line, since these features are claimed in the application 80 above referred to.

While I have described my invention only with reference to a simple shunt-wound machine, it is evidently equally applicable to a compound machine having main field-coils in shunt relation to the armature and other field-coils in series with the armature. In this case 90 the main field-coils remain connected with the line when the connection of the armature and series coils is changed.

What I claim is—

1. The combination, with a car or train of cars on an electric railway, of a braking-generator operated by the motion of the train, having its main field-magnet coils supplied from the line and its armature supplying a local circuit, 100 and an electro-magnetic brake operated by the current in said local circuit, substantially as set forth.

2. The combination, with a car or train of cars on an electric railway, of a braking-generator 105 operated by the motion of the train, having its main field-magnet coils supplied from the line and its armature supplying a local circuit, an electro-magnetic brake operated by the current in said local circuit, and means for regulating the strength of said field-magnet, substantially as set forth.

3. The combination, with a car or train of cars on an electric railway, of a braking-generator 115 operated by the motion of the train, having its main field-magnet coils supplied from the line and its armature supplying a local circuit, an electro-magnetic brake operated by the current in said local circuit, and an adjustable resistance for regulating the current supplied 120 to said main field-coils, substantially as set forth.

4. The combination, with a car or train of cars on an electric railway, of a braking-generator 125 operated by the motion of the train, having its main field-coils supplied from the line and its armature supplying a local circuit, an electro-magnetic brake operated by the current in said local circuit, and an adjustable resistance in said local circuit, substantially as set forth.

5. The combination, with a car or train of cars on an electric railway, of a dynamo-electric machine having its armature-shaft mechanically connected with a driving-axle, and its 130

main field-coils supplied from the line, means for electrically connecting the armature either with the line or with a local circuit, and an electro-magnetic brake operated by current in said local circuit, substantially as set forth. 5

6. The combination, with a car or train of cars on an electric railway, of a dynamo-electric machine having its armature-shaft mechanically connected with a driving-axle and its main field-coils supplied from the line, means for electrically connecting the armature with either the line or a local circuit, an electro-magnetic brake operated by current in said local circuit, and means for regulating the strength of the field-magnet, substantially as set forth. 10

7. The combination of a car or train of cars on an electric railway, a dynamo-electric machine having its armature-shaft mechanically connected with a driving-axle and having its main field-magnet coils supplied from the line, an electro-magnetic brake, a local armature- 15

circuit, means for connecting said local circuit with the magnet or magnets of said brake, and means for connecting the line with said magnet or magnets, substantially as set forth. 25

8. The combination, with a car-wheel, of a brake comprising an electro-magnet having a fixed core and a movable extension of said core in proximity to said wheel, and a circuit for energizing said magnet, substantially as set forth. 30

9. The combination, with two car-wheels, of an electro-magnet between the same having a movable core and two pivoted extensions, each of which is in proximity to one of said wheels, and a circuit for energizing said magnet, substantially as set forth. 35

This specification signed and witnessed this 7th day of November, 1885.
